UNITED STATES PATENT OFFICE.

GEORGE CREIGHTON WEBB, OF NEW YORK, N. Y.

DESIGN FOR A BUTTON.

SPECIFICATION forming part of Design No. 31,619, dated October 10, 1899.

Application filed July 8, 1899. Serial No. 723,249. Term of patent 14 years.

To all whom it may concern:

Be it known that I, GEORGE CREIGHTON WEBB, a citizen of the United States, and a resident of New York city, in the county and State of New York, have invented a certain new and original Design for a Button, of which the following is a specification.

This invention relates to a button for a society-badge of peculiar shape, arrangement of parts, and ornamentation, adopted by and distinctive of the Society of the Army of Santiago. I hereby declare that the accompanying drawings and specification convey a clear understanding of the invention and are sufficient to enable the same to be embodied in the said badge.

The badge is in the form of a button with foot, shank, and head adapted for use in the ordinary buttonhole of a coat-lapel.

20 Figure 1 is a top view of the button. Fig. 2 is a vertical cross-section of the same.

A is the head, B the shank, and C the foot. The inventive design is disclosed in the slightly-conical head, the top of which is characterized by three concentric surfaces of substantially the dimensions delineated, having different horizontal levels and strongly-contrasted colors. Beginning at the center

the inner surface *a* is a disk located in a plane above a circular middle surface *b*, but 30 below a circular outer surface *c*. The inner surface or disk *a* is to be green in color, the middle surface *b* yellow in color, and the circular outer surface *c* red in color. These highly-contrasted colors are essential 35 requisites of the invention and conspire effectively to create a design whose component parts are by their aid distinctly seen to be of different levels and dimensions, respectively, which would not be the case to the ordinary eye 40 were the head all of one color or of very similar colors. A lateral view of the design shows the head as the section of a slightly-conical figure.

What I claim as new, and desire to secure 45 by Letters Patent, is—

The design for a button substantially as shown and described.

In testimony whereof I have signed my name to this specification in the presence of 50 two subscribing witnesses.

G. CREIGHTON WEBB.
